FOUNTAIN PEN

Leon Hehl Ashmore, Collingswood, N. J., assignor
to The Esterbrook Steel Pen Manufacturing
Co., Camden, N. J., a corporation of New
Jersey

Application December 7, 1931, Serial No. 579,605
Renewed March 8, 1933

19 Claims. (Cl. 120—46)

My invention relates to fountain pens of the self-filling type, and the object of my invention is to provide an improved form of presser bar cooperating with the ink-receiving bag or container; such bar being designed to more effectively collapse such bag in connection with the operation of filling the same.

A further object of my invention is to provide a double-acting presser bar arranged to effect collapse or deflation of the ink-receiving bag substantially throughout its entire length. For such purpose the presser bar is divided longitudinally and for the greater part of its active portion into a plurality of parts which are capable of being flexed independently of each other and in opposed relation.

A further object of my invention is to provide an actuating member adapted to engage the several parts of the presser bar and simultaneously flex independently flexible parts of the same so that the desired pressure to compress or deflate the ink-receiving bag may be applied thereto substantially throughout the whole length of the same.

25 And a still further object of my invention is to corrugate the separately flexible parts of the presser bar longitudinally of the same so as to give the desired strength and rigidity to effect the collapsing action without undue weight and 30 without affecting the resiliency and/or flexibility of such parts.

These and other features of my invention are more fully described hereinafter; reference being had to the accompanying drawing, more or 35 less diagrammatic in character, in which:

Figure 1 is a longitudinal elevation, partly in section, of a fountain pen employing my improved presser bar; the latter being shown in the inactive position.

40 Fig. 2 is a similar view showing the presser bar in the position assumed when collapsing or compressing the ink-containing bag.

Fig. 3 is an enlarged sectional view on the line III—III, Fig. 2.

45 Fig. 4 is a perspective view of my improved presser bar on an enlarged scale, and

Fig. 5 is a sectional view of the presser bar on the line V—V, Fig. 4, on a slightly larger scale.

In the drawing, A represents the tubular shell 50 or barrel of the pen; B the pen section carrying the pen b and feeder bar b', and C the ink bag, usually of rubber, which may be attached at c to the inner end of the feeder bar or the pen section B. This is ordinary fountain pen 55 construction and any type of fountain pen hav-

ing these features or elements, or their equivalent, may be equipped with my improved presser bar structure.

The ink-receiving bag C extends substantially throughout the length of the chamber a provided by the shell or barrel A. The presser bar is shown at 10 and includes the reversely bent portion 10^a with the free end 10^b which is under sufficient tension to require slight compression when introduced into the shell or barrel A so that such reversely bent portion of the presser bar with the free end 10^a serves to retain the same in place. The ink-receiving bag may extend into the reversely bent or looped portion 10^a.

Beyond the reversely bent or looped portion 70 10^a the presser bar is divided longitudinally by

slits 10^b into a plurality of separately flexible portions, indicated at 11 and 11^a, and 12; the portions 11 and 11^a being disposed at the sides of such bar and being disconnected at the point 75 x, while the portion 12 is continuous throughout the length of said presser bar. This arrangement is such as to provide a plurality of flexible fingers, three in the present instance, to act upon the

ink-receiving bag when actuated by the lever 80 common to self-filling pens. This lever, indicated at 13, is pivotally connected to the barrel or shell A of the pen. The common practice is

to provide a spring ring of suitable size and suitable gauge metal such as indicated at 14 which 85 serves as a pivot for such lever; the balance of the ring forming such pivot being disposed in an annular groove a' formed on the inner wall of the shell or barrel A.

The lever 13 lies in a slot A' in the shell or barrel A and has a grasping end 13^a, slightly reduced, which lies in a recess a² formed in the barrel or shell A just beyond the slot A'; such end 13^a being convenient of engagement by the finger-

nail or a suitable instrument so as to be raised 90 for cooperative engagement of its opposite end with the several portions of presser bar 10. The actuating end of the lever 13 is preferably bifurcated, as clearly shown in Fig. 3, and the position

of the presser bar within the shell or barrel A 95 with respect to such operative end of the lever

is such the legs 13^b of the same will first engage the portions 11 and 11^a of the presser bar whose

fulcrum, so to speak, is at the point x', and after further movement of the lever, the central portion 12 of the presser bar is engaged by the central portion 13^c of the lever 13, and when

such lever is finally disposed in the position shown in Figs. 2 and 3, the ink-receiving bag C will have been collapsed to the desired extent as 110

indicated in these views; the portions 11 and 11^a effecting collapse or compression of such bag adjacent the rear end of the barrel or shell A, while the portion 12 effects collapse or compression at the forward end of the bag. By the employment of the presser bar such as I have devised the pressure to collapse or deflate the bag is distributed substantially throughout the length of the bag; making for a more complete collapse or compression of the bag and facilitating the intake of a greater quantity of ink to fill the bag upon release of the lever than is possible with presser bars having a single portion acting from a single fulcrum point adjacent one end of the shell or barrel under the influence of the usual lever carried thereby.

By preference the active portion of the presser bar is made of a corrugated section of suitable spring metal, as clearly shown in Figs. 4 and 5; each portion; 11, 11^a and 12, being corrugated. And such corrugations may extend throughout the full extent of the presser bar or the active portions alone may be corrugated. Such corrugations add a certain amount of stiffness and strength to the portions 11, 11^a and 12 of the presser bar without affecting the desired resiliency or flexibility or the ability of such portions to bend and automatically develop fulcrum points without destroying the elastic limit of the metal comprising such presser bar.

I claim:

1. The combination with the shell or barrel of a fountain pen and a flexible ink-containing bag disposed therein and operatively associated with the fountain pen, of a presser bar having a plurality of separately flexible fingers, and means for causing said separately flexible fingers to collapse or compress the ink-containing bag.

2. The combination with the shell or barrel of a fountain pen and a flexible ink-containing bag disposed therein and operatively associated with the fountain pen, of an integral presser bar slit longitudinally to provide a plurality of separately flexible fingers, and means for causing said separately flexible fingers to collapse or compress the ink-containing bag.

3. The combination with the shell or barrel of a fountain pen and a flexible ink-containing bag disposed therein and operatively associated with the fountain pen, of a presser bar having a plurality of separately flexible fingers, and a lever for engaging said separately flexible fingers to collapse or compress the ink-containing bag.

4. The combination with the shell or barrel of a fountain pen and a flexible ink-containing bag disposed therein and operatively associated with the fountain pen, of an integral presser bar slit longitudinally to provide a plurality of separately flexible fingers, and a lever constructed to successively engage said separately flexible fingers to collapse or compress the ink-containing bag.

5. The combination with the shell or barrel of a fountain pen and a flexible ink-containing bag disposed therein and operatively associated with the fountain pen, of a presser bar having a plurality of separately flexible fingers arranged in opposed relation for compressing or collapsing such bag, and movable means for engaging said separately flexible fingers.

6. The combination with the shell or barrel of a fountain pen and a flexible ink-containing bag disposed therein and operatively associated with the fountain pen, of an integral presser bar slit longitudinally to provide a plurality of separately flexible fingers arranged in opposed relation

for compressing or collapsing such bag, and movable means for engaging said separately flexible fingers.

7. The combination with the shell or barrel of a fountain pen and a flexible ink-containing bag disposed therein and operatively associated with the fountain pen, of a presser bar having a plurality of separately flexible fingers arranged in opposed relation for compressing or collapsing such bag, and a pivoted lever carried by the fountain pen barrel and constructed and arranged to successively engage said separately flexible fingers.

8. The combination with the shell or barrel of a fountain pen and a flexible ink-containing bag disposed therein and operatively associated with the fountain pen, of a presser bar having a plurality of separately flexible corrugated fingers for compressing or collapsing such ink bag, and means for moving said fingers.

9. The combination with the shell or barrel of a fountain pen and a flexible ink-containing bag disposed therein and operatively associated with the fountain pen, of an integral presser bar longitudinally corrugated and slit to provide a plurality of separately flexible corrugated fingers for compressing or collapsing such ink bag, and a pivotally mounted lever for successively engaging such fingers.

10. The combination with the shell or barrel of a fountain pen and a flexible ink-containing bag disposed therein and operatively associated with the fountain pen, of a presser bar having a plurality of separately flexible corrugated fingers for compressing or collapsing such ink bag, and a pivotally mounted lever for successively engaging such fingers.

11. The combination with the shell or barrel of a fountain pen and a flexible ink-containing bag disposed therein and operatively associated with the fountain pen, of a presser bar having a plurality of separately flexible corrugated fingers in opposed relation for compressing or collapsing such ink bag, and a pivotally mounted lever for separately engaging such fingers.

12. The combination with the shell or barrel of a fountain pen and a flexible ink-containing bag disposed therein and operatively associated with the fountain pen, of an integral presser bar longitudinally corrugated and slit to provide a plurality of separately flexible corrugated fingers in opposed relation for compressing or collapsing such ink bag, and a pivotally mounted lever for separately and successively engaging such fingers.

13. The combination with the shell or barrel of a fountain pen and the usual flexible ink-containing bag disposed therein, of a presser bar having a plurality of separately flexible fingers for compressing or collapsing such ink bag, and a pivotally mounted lever having a bifurcated end for separately and successively engaging such fingers.

14. The combination with the shell or barrel of a fountain pen and the usual flexible ink-containing bag disposed therein, of an integral presser bar longitudinally slit to provide a plurality of separately flexible fingers in opposed relation for compressing or collapsing such ink bag, and a pivotally mounted lever having a bifurcated end for separately and successively engaging such fingers.

15. The combination with the barrel of a fountain pen and a flexible ink-containing bag disposed therein and operatively associated with the fountain pen, of an integral presser bar slit longi-

5 titudinally to provide a plurality of separately flexible fingers arranged in opposed relation for compressing such bag; a plurality of said fingers having free ends, and movable means for engaging said separately flexible fingers.

10 16. The combination with the barrel of a fountain pen and a flexible ink-containing bag disposed therein and operatively associated with the fountain pen, of an integral presser bar having a plurality of separately flexible fingers for compressing such bag; a plurality of said fingers having free ends, and movable means for engaging said separately flexible fingers.

15 17. The combination with the barrel of a fountain pen and a flexible ink-containing bag disposed therein and operatively associated with the fountain pen, of a presser bar having a plurality of separately flexible fingers arranged in opposed relation for compressing such bag; a plurality of said fingers having free ends, and a lever for engaging each of said separately flexible fingers.

18. The combination with the barrel of a fountain pen and a flexible ink-containing bag disposed therein and operatively associated with the fountain pen, of a presser bar having a plurality of separately flexible fingers arranged in opposed relation for compressing such bag; a plurality of said fingers having free ends, and a pivoted lever carried by the fountain pen barrel and constructed and arranged to engage each of said separately flexible fingers.

80 19. The combination with the barrel of a fountain pen and a flexible ink-containing bag disposed therein and operatively associated with the fountain pen, of an integral presser bar longitudinally corrugated and slit to provide a plurality of separately flexible corrugated fingers for compressing such ink bag; a pair of said fingers having free ends, and a pivotally mounted lever for engaging each of said corrugated fingers.
